UNITED STATES PATENT OFFICE.

EDWARD E. BRADLEY, OF STONINGTON, CONNECTICUT, ASSIGNOR TO THE ATWOOD MACHINE COMPANY, OF STONINGTON, CONNECTICUT, A CORPORATION OF NEW JERSEY.

BOBBIN-WINDING MACHINE.

1,257,182.

Specification of Letters Patent. Patented Feb. 19, 1918.

Application filed July 3, 1915. Serial No. 37,930.

To all whom it may concern:

Be it known that I, EDWARD E. BRADLEY, a citizen of the United States, and resident of Stonington, in the county of New London 5 and State of Connecticut, have invented a new and useful Improvement in Bobbin-Winding Machines, of which the following is a specification.

In bobbin winding machines as heretofore constructed, the take-up bobbins are held in a swinging hanger so that the weight 10 of the hanger will hold the bobbins down upon their driving drums thus giving the necessary tension to draw the thread.

15 In machines of this character, the bobbins are run upon a loose gudgeon and when it is desired to doff the bobbins it is necessary to remove the bobbins and their loose gudgeons from the hanger. This is an awkward 20 operation and frequently allows the bobbins and their gudgeons to drop onto the floor thereby causing much delay in the operation of doffing.

25 The object of my invention is to provide a structure in which the loose gudgeon is obviated and, at the same time, retain the downward pressure on the gudgeon. To accomplish this, I make each hanger in two members, in one of which members one end 30 of the gudgeon is rotatably but not removably mounted, the other end of the gudgeon being arranged to be brought into and out of its bearing in the other member of the hanger.

35 In the operation of winding, it is frequently necessary to piece up the ends of the take-up bobbin and to accomplish this I have provided a structure in which the two members of the hanger may be raised together 40 to lift the bobbin from its driving drum.

When it is desired to doff the bobbin, I have provided means for further lifting the member of the hanger which carries the 45 gudgeon and bobbin away from the other member of the hanger a sufficient distance to remove the bobbin from the gudgeon.

A practical embodiment of my invention is represented in the accompanying drawings, in which

50 Figure 1 represents in end elevation my improved hanger attached to the longitudinal bars of the winding machine, the parts

being in the positions which they assume when the bobbin is resting on its driving 55 drum,

Fig. 2 is a top plan view of the same,

Fig. 3 is a view of the hanger and its adjacent parts taken from the opposite end from Fig. 1, the parts being shown in full 60 lines in the positions which they assume when the bobbin has been lifted for piecing up the thread, the position of the parts as shown in Fig. 1 being shown in dotted lines in this figure,

65 Fig. 4 is a view similar to Fig. 3 with the parts in the positions which they assume when one member of the hanger has been raised from the other member to permit the doffing of the bobbin, and

70 Fig. 5 is a front view of the hanger and its adjacent parts with the parts in the positions shown in Fig. 3.

75 The longitudinal bars of the winding machine are denoted by 1, to which the supporting bracket 2 is clamped in the usual manner by the shoe 3 and bolt 4. The bracket is provided with uprising sides 5, 6, and from the base of the bracket, arms 7, 8, project in opposite directions. As all of the 80 hangers and their operating parts are the same, I will describe only one of said hangers and its operating parts herein.

85 An auxiliary bracket 9 is secured to the uprising side 5 by bolts 10 by means of which the hanger as a whole can be alined for the purpose of squaring the axis of the bobbin with respect to the axis of its driving drum 11. This auxiliary bracket 9 is provided with an axle pin 12 on which are 90 loosely hinged the inner ends of the arms 13, 14, of one member of the hanger and the inner ends of the arms 15, 16, of the other member of the hanger. The other end of the arm 14 of the hanger is provided with a 95 cross piece 17 connecting it with the arm 13 at a distance outwardly from the hinged end of said arm.

100 A cross piece 18 connects the outer end of the arm 15 with the arm 16 at a distance outwardly from the hinged end of the arm 16.

105 The two members of the hanger overlap each other so that they may be moved together during a portion of their swinging movement by a swinging operating

means, as will hereinafter more fully appear.

The bobbin is denoted by 19 and it is mounted upon a gudgeon 20, one end of which is rotatably carried by the arm 16 of one member but is held against removal therefrom by means of a pin 21 extending into a circumferential groove 22 in the end of the gudgeon within the lug 23.

- 10 The other end of the gudgeon 20 is adapted to rest in bearings carried by the arm 13 of the other member of the hanger, said bearings being provided in a spring actuated latch 24 hinged at 25 to the said arm 13 and held yieldingly at the limit of its inward movement by a coil spring 26 against a stop 27 on the arm 13.

A spring 28 connects the arm 16 with the auxiliary bracket 9, which spring tends 20 to press both members of the hanger downwardly to bring the bobbin 19 into driving engagement with its drum 11. This is accomplished because of the overlapping of the arms 14, 15, of the two members of 25 the hanger.

An arm 29 on the auxiliary bracket 9 is provided with an adjustable screw 30 acting as a stop for limiting the upward movement of the hanger which carries the gudgeon 20.

The spring 28 is so located that when the said gudgeon carrying member of the hanger is in its fully raised position, the spring will hold it in this position by the 35 swinging of the axis of the spring to a point above the axis of the said hanger member.

An operating lever 31 is pivoted at 32 to the arm 7, which lever is provided with 40 two laterally projecting pins 33, 34. The pin 33 is arranged to be brought into operative engagement with the under side of the arm 13 for moving the arm and thereby both members of the hanger upwardly as 45 the lever is moved forwardly. The pin 34 is arranged in position to engage the cam surface 35 of the spring catch 24 as the lever is swung forwardly for the purpose of releasing the free end of the gudgeon 20 50 from its bearing in the said catch 24 to permit the further upward movement of the gudgeon carrying member for the purpose of doffing the bobbin.

In operation, assuming the parts to be in 55 the position shown in Fig. 1, with the hanger dropped down to bring the bobbin into its driving engagement with the drum and the operating lever in its raised or released position, the forward swinging 60 movement of the lever will, because of the engagement of its pin 33 with the under side of the arm 13, lift both members of the hanger and thereby raise the bobbin from its driving engagement with the 65 drum. In this position, the ends of the

threads may be pieced up if they have become broken and the lever may be swung rearwardly to permit the hanger to again drop down to bring the bobbin into driving engagement with the drum.

70

If it be desired to doff the bobbin, the lever 31 is swung to the limit of its forward movement and during this movement the pin 33 will lift both members of the hanger together and the pin 34 will swing the 75 catch 24 to release the free end of the gudgeon 20. The gudgeon carrying member of the holder may then be lifted away from the other member a sufficient distance to permit the bobbin to clear the said other 80 member when being doffed from the gudgeon.

It will be understood that the spring 28 will hold the gudgeon carrying member in its raised position until the member is 85 again swung downwardly into engagement with the other member of the hanger.

If so desired, the under side of the arm 13 may be provided with a recess 36 for receiving the pin 33 when the lever has been 90 swung a sufficient distance forwardly to raise the hanger sufficiently to cause the bobbin to clear its drum.

An adjacent recess 37 may also be provided for receiving the pin 33 when the 95 lever is swung into position to operate the catch to release the free end of the gudgeon. However, the recess 36 is not essential to the operation of the device for the piecing up might just as well be accomplished when the lever is moved to the limit of its forward movement as when in an intermediate position.

It will be seen from the above description that by dividing the bobbin hanger, the gudgeon may be permanently carried by one of 105 the members thus eliminating all liability of dropping or losing the gudgeon during the doffing of the spindle.

It will also be seen that a very rapid 110 doffing and replacement of the bobbins may be accomplished and also that the peculiar construction of the members of the hanger permit the utilization of a single lever for raising the members together to permit the 115 piecing up of the thread when so desired.

It is evident that slight changes may be resorted to in the form, construction and arrangement of the several parts without departing from the spirit and scope of my invention; hence I do not wish to limit myself strictly to the structure herein set forth, but

What I claim is:—

1. A hanger for bobbins comprising two 125 separable members, a bobbin gudgeon secured to one member, a catch on the other member for removably engaging the free end of the gudgeon and a single operating lever for controlling the movement of the members into and out of the bobbin winding 130

position and also the releasing of the catch to permit the separation of the members for doffing the bobbin.

2. A hanger for bobbins comprising two separable members, a bobbin gudgeon rotatably secured to one member, a catch on the other member for removably engaging the free end of the gudgeon, a single operating lever for controlling the movement of the members into and out of the bobbin winding position and also the releasing of the catch to permit the separation of the members for doffing the bobbin, and a spring arranged to yieldingly hold the members in the bobbin winding position and also to yieldingly hold the members in their separated position.

3. A hanger for bobbins comprising two separable members hinged along a common axis, a bobbin gudgeon secured to one member, a catch on the other member for removably engaging the free end of the gudgeon, and a single operating lever for controlling the movements of the members into and out of the bobbin winding position and also for releasing the catch to permit the separation of the members for doffing the bobbin from the gudgeon.

4. A hanger for bobbins comprising two members hinged along a common axis, said members overlapping each other, a lever engaging one member for moving both members out of the bobbin winding position and a spring engaging the other member for moving both members into the bobbin winding position when released by the lever, the spring engaged member being separable from the lever engaged member to permit the doffing of the bobbin.

5. A hanger for bobbins comprising two members hinged along a common axis, said members overlapping each other, a lever engaging one member for moving both members out of the bobbin winding position, a spring engaging the other member for moving both members into the bobbin winding position when released by the lever, the spring engaged member being separable from the lever engaged member to permit the doffing of the bobbin, and a gudgeon secured to the spring engaged member.

In testimony that I claim the foregoing as my invention, I have signed my name this 7th day of June, 1915.

EDWARD E. BRADLEY.
